[57] CLAIM

The ornamental design for a combined paper tray and
paperweight, as shown and described.

DESCRIPTION

FIG. 1 is a top plan view of a combined paper tray and
paperweight showing my new design;

FIG. 2 is a bottom plan view;

FIG. 3 is a front elevational view;

FIG. 4 is a rear elevational view;

FIG. 5 is a left side elevational view;

FIG. 6 is a right side elevational view;

FIG. 7 is a top plan view of an alternate embodiment of
the combined paper tray and paperweight; and

FIG. 8 is a bottom perspective view thereof.
